NEEDLE THREADER

Roy E. Gearhart, Kansas City, Mo., assignor of one-half to Charles E. Hose, Kansas City, Mo., and one-half to Earl A. Hose, Marietta, Ga.

Application February 28, 1949, Serial No. 78,716

5 Claims. (Cl. 223—99)

1

This invention relates to new and useful improvements in needle threaders, and has particular reference to needle threaders of the portable, hand-operated type.

The principal object of the present invention is the provision of a needle threader including a pair of thin resilient blades adapted to be extended through the eye of a needle, and to function as a pair of tweezers to grip a thread and pull a loop thereof through the eye of the needle.

Another object is the provision, in a needle threader of the class described, of means whereby, as the needle is inserted into the threader, the eye of said needle is placed in alignment with the blades, in order that the needle may be threaded without the necessity of seeing the needle eye at any time.

A further object is the provision of a needle threader adapted to thread either the ordinary hand needle or a sewing machine needle, the latter without removing the needle from its normal position in the sewing machine.

Other objects are simplicity and economy of construction, ease, efficiency, and convenience of operation, and adaptability without adjustment, to thread needles of a wide range of sizes.

With these objects in view, as well as other objects which will appear in the course of the specification reference will be had to the drawing, wherein:

Figure 1 is a side elevation of a needle threader embodying the present invention.

Fig. 2 is an end view of the threader shown in Fig. 1.

Fig. 3 is an enlarged sectional view taken on line III—III of Fig. 1, with parts left in elevation.

Fig. 4 is a fragmentary view similar to Fig. 3, showing a needle inserted in the threader preparatory to threading, with parts broken away.

Fig. 5 is a section taken on line V—V of Fig. 4, with the needle omitted.

Fig. 6 is an enlarged fragmentary section taken on line VI—VI of Fig. 4, showing the method by which the needle is turned axially as it is inserted in the threader to present its eye to the threading blades.

Fig. 7 is a sectional view taken on line VII—VII of Fig. 4, with the blades extended through the needle eye and a thread positioned therebetween.

Fig. 8 is a view similar to Fig. 7, showing the threader in operative relationship to a sewing machine needle, and with the blades extended to engage the eye of said needle.

2

Fig. 9 is a section taken on line IX—IX of Fig. 3.

Fig. 10 is a section taken on line X—X of Fig. 3.

Like reference numerals apply to similar parts throughout the several views, and the numeral 2 refers to a tubular casing made of plastic, metal, wood, or other suitable material. A flat cylindrical head 4, preferably made of metal, is provided with an axially extending reduced shank 6 which is fitted tightly and permanently into the upper or forward end of casing 2. Head 4 and shank 6 have a cylindrical bore 8 extending therethrough. A tube 10 is pressed tightly into bore 8, said tube being disposed axially in casing 2 and having its lower, or rearward, end substantially flush with the lower end of said casing. At its upper end, tube 10 is formed to present a pair of longitudinally extending fingers 12 disposed on diametrically opposite sides of said tube. Said fingers extend substantially flush with the upper surface of head 4, and are turned inwardly at their upper ends to form spaced apart, parallel, planar guides 14 parallel to the axis of tube 10 and spaced equally on opposite sides of said axis.

Said guides are spaced apart just sufficiently that a pair of blades 16 disposed together may slide freely therebetween. Said blades are identical, and comprise elongated narrow strips of spring steel. Their width is less than the length of the shortest needle eye which it is intended to thread, and their thickness is such that when the blades are flat against each other, they will pass freely through the needle eye. A blade thickness of one to one and a half thousandths of an inch has been found satisfactory. At their inner ends, blades 16 are fixed to the end of an operating rod 18, said rod being carried slidably in tube 10 and projecting outwardly from the lower end thereof. Adjacent the lower end of tube 10, rod 18 is notched as at 20, and a portion of the wall of tube 10 is offset inwardly to form a lug 22 projecting into said notch. This lug prevents rod 18 from rotating axially in tube 10, thereby maintaining blades 16 in alignment with guides 14, and also provides limits for the sliding movement of the rod in the tube. At its lower end rod 18 is securely fixed in a plunger 24 which fits slidably in an enlarged axial bore 26 provided in the lower end of casing 2, and which is provided with an axial recess 28 for slidably receiving tube 10. A coil spring 30 disposed about rod 18 within recess 28 bears at one end against the bottom of said recess and at its opposite end against the lower end of tube 10, thereby urging

plunger 24 and operating rod 18 downwardly. It will be noted in Fig. 3 that when the plunger is in its normal or downwardly extended position, the upper ends of blades 16 are disposed just beneath the upper surface of head 4.

The needle to be threaded is positioned to receive blades 16 by the following mechanism, which utilizes the fact that in virtually all needles, the eye portion thereof is slightly broadened and flattened, so that the thickness of the needle along the axis of the eye is less than the thickness across the eye. A metal plate 32 somewhat thinner than the diameter of the smallest needle to be threaded is soldered or otherwise fixed flat against the planar upper surface of head 4, and forms a part of said head. As best shown in Fig. 5, plate 32 is radially slotted at 34. The centerline of said slot lies in the plane of blades 16 and the slot is slightly wider than the diameter of the largest needle to be threaded. Said slot extends across the center of head 4 to expose the upper end of guides 14 and blades 16, and is taperingly reduced at its inner end as at 36. A small upright stop 38 is provided on plate 32 at the inner end of slot 34.

A flat, substantially cylindrical cap 40 is normally disposed flat against the upper surface of plate 32. Said cap is provided with a depending ear 42 which extends into a slot 44 cut radially in head 4 in line with slot 34 but at the opposite side of the head, as clearly shown in Figs. 3 to 5. Cap 40 is supported pivotally on pivot pin 46 which extends through ear 42 and head 4 at right angles to the axis of slot 34. A compression spring 48 bearing respectively at its opposite ends in suitable sockets formed in head 4 and in the lower end portion of ear 42, serves to press cap 40 firmly against plate 32. Cap 40 is notched inwardly from its edge at 50. Said notch is of sufficient extent to uncover the inner end portion of slot 34 and stop 38, and it will be noted that wall 52 of said notch, which traverses slot 34, is disposed at right angles to said slot and as close as possible to the line of travel of blades 16, as shown in Fig. 4. A V-groove 54 is formed across the upper surface of cap 40 in alignment with slot 34, for a purpose hereinafter appearing.

In operation, when it is desired to thread an ordinary hand needle 56, the needle is inserted eye end first into slot 34 of plate 32. Head 4 and cap 40 are counterbored at the outer end of slot 34 to provide a bell mouth 58, thereby permitting easy insertion of the needle. Since plate 32, and hence slot 34, is thinner than the needle, the needle forces cap 40 upwardly, as shown in Figs. 4 and 6, pivoting it about pin 46 against the pressure of spring 48. Then, since the needle is wider across the eye than through the eye, the resilient pressure of cap 40 thereon will cause the needle to rotate axially until the eye 60 thereof is disposed vertically, as shown in Fig. 6. When the needle reaches the inner end of slot 34, it will be centered transversely in the slot by the tapered portion 36 of said slot, and will be stopped thereby with the eye positioned to receive blades 16. Stop 38 serves to prevent the needle from completely overshooting the end of notch 34 in any circumstance. It will be noted in Fig. 4 that when the needle is fully inserted, cap 40 contacts the needle only at the lower edge of wall 52 thereof. This point of contact is designated at 62 and is quite close to the needle eye. Since the flattened portion of the needle extends substantially below the actual eye aperture 60, wall 52 of the cap contacts said flattened portion and main-

tains the needle eye in alignment with the blades 16. The shank portion of the needle is not contacted by the cap, due to the tilting of the cap. This is an advantage since in many needles the shank is somewhat thicker than the dimension through the eye. If the cap contacted the shank, it would be forced out of contact with the flattened eye portion, and the needle might then rotate.

While the above described arrangement is sufficient in most cases to position the needle eye to receive the blades 16, it has been found that certain very small needles will advance so far into tapered portion 36 of slot 34 that eye 60 thereof partially overshoots the ends of blades 16, as shown in Fig. 4. To overcome this difficulty, the tips of blades 16 are bevelled toward the open end of slot 34, as shown at 64. Thus when plunger 24 is pressed inwardly to advance blades 16 through the needle eye 60, the pointed blade tips will first enter the portion of the eye closest to the needle point, and bevelled edges 64 will force the needle outwardly in slot 34 until the blades enter the eye.

When blades 16 have been extended through the needle eye, the extended end portions thereof assume the shape shown in Fig. 7, being bent outwardly or divergently at 66 and being rebent slightly inwardly at their tips as at 68. A thread 70 is then laid between the widely spaced tips of the blades, as shown in Fig. 7, and plunger 24 is released, whereupon it will be forced downwardly by spring 30. As the blades are drawn through the needle eye, the tips thereof will be brought into contact while portions 68 are still spaced apart. This prevents the thread from being crowded out between the ends of the blades. The blades have sufficient rigidity so that when only a short portion thereof extends above the needle, they will function as a pair of tweezers and grip the thread therebetween with sufficient force to pull a loop thereof through the eye of the needle. When the blades are fully retracted, the needle may be turned slightly in a horizontal plane to remove it from slot 34 and bring it within notch 50 of cap 40. The needle is then free and may be drawn away from the threadder, thereby pulling the thread through the needle eye. When sufficient thread has been pulled through the eye of the needle, a slight pull on the thread will disengage it from the blades.

In a sewing machine the needle is held rigidly, with the eye thereof always disposed in a given line. In using the threadder on sewing machine needles, therefore, the threadder is held against the side of the needle 72, with the casing 2 disposed in the known direction of the eye. The needle is engaged by V-groove 54 of cap 40, which centers the needle transversely of the threadder blades, as shown in Fig. 8. A gentle pressure may then be exerted on plunger 24 until the blades contact the side of the needle. The threadder is then moved longitudinally along the needle until the blades register with and enter the needle eye. It is not deemed practical to provide longitudinal stops for a sewing machine needle, since the distance from the needle eye to the point varies widely. However, it is quite apparent that for sewing machine needles wherein the eye-to-point distance is equal, a stop could be placed in groove 54 to position the needle eye properly with respect to the threadder blades. It will be noted that a sewing machine needle disposed in groove 54 is substantially farther away from blade guides 14 than a hand needle disposed

in slot 34, and that hence the blades must extend unsupported from said guides a substantial distance before passing through the eye of the sewing machine needle. This shows clearly in Fig. 8. However, the inward bends 68 of the blades insure that the tips of the blades will be pressed firmly together by their own resiliency until they are extended sufficiently far to enter the eye of needle 72.

While I have disclosed a specific embodiment of my invention, it is apparent that many variations of construction and operation could be made without departing from the spirit of the invention, and it is therefore requested that my protection extend to all subject matter properly falling within the scope of the appended claims.

What I claim is:

1. A needle threader comprising a head having a planar surface, a pair of elongated resilient planar blades normally disposed beneath the surface of said head, means for extending said blades above the surface of said head, said head having a slot formed in the surface thereof substantially radially related to said blades and lying in alignment with the major cross-sectional axes of said blades, and a stop at the inner end of said slot whereby a needle inserted longitudinally in said slot will be longitudinally positioned with its eye directly over said blades, the upper ends of said blades being tapered away from said stop.

2. A needle threader comprising a head having a planar upper surface, a pair of flat, elongated, resilient blades normally disposed beneath the surface of said head, means for extending said blades above the surface of said head substantially at right angles thereto, through an orifice provided in said head, said blades being normally divergent, fixed parallel guides at said orifice for maintaining said blades together at the point of exit from said head, said head having a flat bottomed radial slot formed in the upper surface thereof and extending across said blade orifice, said slot being disposed in alignment with the major cross-sectional axes of said blades and having taperingly convergent lateral walls at its inner end, said slot also being wider than the diameter of the needle to be threaded but shallower than the diameter of said needle, a planar cap carried pivotally by said head, and resilient means urging said cap against the upper surface of said head.

3. A needle threader comprising a head having a planar upper surface, a pair of flat, elongated, resilient blades normally disposed beneath the surface of said head, means for extending said blades above the surface of said head substantially at right angles thereto, through an orifice provided in said head, said blades being normally divergent, fixed parallel guides at said orifice for maintaining said blades together at the point of exit from said head, said head having a flat bottomed radial slot formed in the upper surface thereof communicating with said blade orifice and disposed in alignment with the major cross-sectional axes of said blades, said slot being shallower than the diameter of the needle being threaded, and a planar cap normally disposed flat

against the upper surface of said head, said cap being carried pivotally by said head for movement away from said head on an axis at right angles to said slot, and resilient means urging said cap against said head.

4. A needle threader comprising a head having a planar upper surface, a pair of flat, elongated, resilient blades normally disposed beneath the surface of said head, means for extending said blades above the surface of said head substantially at right angles thereto, through an orifice provided in said head, said blades being normally divergent, fixed parallel guides at said orifice for maintaining said blades together at the point of exit from said head, said head having a flat bottomed radial slot formed in the upper surface thereof communicating with said blade orifice and disposed in alignment with the major cross-sectional axes of said blades, said slot being shallower than the diameter of the needle being threaded, and a planar cap normally disposed flat against the upper surface of said head, said cap being carried pivotally by said head for movement away from said head on an axis at right angles to said slot, said head having a flat bottomed radial slot formed in the upper surface thereof communicating with said blade orifice and disposed in alignment with the major cross-sectional axes of said blades, said slot being shallower than the diameter of the needle being threaded, and a planar cap normally disposed flat against the upper surface of said head, said cap being carried pivotally by said head for movement away from said head on an axis at right angles to said slot, said cap being notched inwardly from its edge to uncover said blade orifice and the inner end portion of said slot, the wall of said notch which traverses said slot being disposed at right angles to said slot, and resilient means urging said cap toward said head.

5. A needle threader comprising a head having a planar upper surface, a pair of flat, elongated, resilient blades normally disposed beneath the surface of said head, means for extending said blades above the surface of said head substantially at right angles thereto, through an orifice provided in said head, fixed parallel guides at said orifice for maintaining said blades together at their point of exit from said head, said blades being so formed that when extended they will diverge adjacent said guides and converge slightly at their tips, said head having a radial slot formed in the upper surface thereof communicating with said blade orifice and disposed in alignment with the major cross-sectional axes of said blades, said slot being shallower than the diameter of the needle to be threaded, and a planar cap carried movably by said head and normally disposed against the upper surface thereof, said cap having a V-groove formed diametrically across the upper surface thereof in alignment with said slot.
